United States Patent

Des. 237,606
Patented Nov. 11, 1975

237,606

WESTERN STYLE BUILDING

Ruut van den Hoed, Valley Forge, Pa., assignor to
The Rustler, Inc., King of Prussia, Pa.

Filed July 30, 1973, Ser. No. 383,853

Term of patent 14 years

Int. Cl. D25—03

U.S. Cl. D13—1 B

FIG. 1

FIG. 3

FIG. 2

FIG. 4

FIG. 1 is a front elevation view of a Western style building in accordance with the present invention;

FIG. 2 is a left side elevation view thereof;

FIG. 3 is a rear elevation view thereof;

FIG. 4 is a right side elevation view thereof; and

FIG. 5 is a top plan view thereof.

I claim:

The ornamental design for a Western style building, substantially as shown and described.
